UNITED STATES PATENT OFFICE.

VIRDA R. BROWN, OF GARFIELD, KENTUCKY.

MACHINE FOR TRIMMING AND CUTTING WALL-PAPER.

1,231,845.

Specification of Letters Patent.

Patented July 3, 1917.

Application filed February 25, 1916. Serial No. 80,491.

To all whom it may concern:

Be it known that I, VIRDA R. BROWN, a citizen of the United States, residing at Garfield, in the county of Breckinridge, State of Kentucky, have invented a new and useful Machine for Trimming and Cutting Wall-Paper; and I do hereby declare the following to be a full, clear, and exact description of the invention, such as will 10 enable others skilled in the art to which it appertains to make and use the same.

This invention relates to a machine for trimming wall paper, and an object of the invention is to provide a machine of this 15 design which involves improved features of construction.

One of the features of construction is the provision of improved trimming means for trimming the paper as it leaves the roll, and 20 to suspend the trimming means under the table to prevent the cutting edges of the trimming members from being injured.

Another object of the invention is to provide guides for the paper, and which guides 25 support the trimming members, the guides being adjustable toward each other to accommodate paper of different widths.

In practical fields the details of construction may necessitate alterations, falling 30 within the scope of what is claimed.

The invention comprises further features and combination of parts, as hereinafter set forth, shown in the drawings and claimed.

In the drawings:

35 Figure 1 is a view in perspective of a portion of a paper hanger's table, showing the trimming and guiding means for the wall paper, at a point adjacent a pasting mechanism on the table, whereby the paper 40 may be guided to and between the pasting rolls.

Fig. 2 is a detail view of one of the paper guides and trimmer.

Fig. 3 is a detail perspective view of the 45 other paper guide and trimmer.

Fig. 4 is a detail sectional view through one of the guides, showing the trimming means.

50 Fig. 5 is a detail sectional view of a pasting mechanism at one end of a paper hanger's table, showing the invention consisting of the guiding and trimming means as applied adjacent the pasting mechanism for trimming the paper and guiding the 55 same between the rolls of the pasting mechanism.

Referring more especially to the drawings, there is shown a portion of a paper hanger's table, whereby wall paper may be supplied with paste as the paper is unreeled and laid on the table. The table has suitable sides 26. Extending transversely of and connecting the sides of the table is a strip 6, extending from which are longitudinal strips 9 for the support of wall 65 paper, as it is trimmed and supplied with paste. Connecting the sides 26 of the table are transverse rods 27 and 28, which are engaged by the hooks 29 of the paste receptacle 30, for supporting said receptacle. 70 Upon the inner faces of said sides 26 plates 31 are secured as at 32. These plates 31 are provided with diverging oppositely disposed bearing slots 33 and 34. The oppositely disposed slots 33 receive the pintles 35 of the roller 36, over which the wall paper 37 from the roll 38 of paper travels, as the paste is applied to the wall paper by the paste roller 39. The oppositely disposed slots 34 receive the ends of 75 the rod 40, on which the angular levers 41 are pivoted. The lower ends of the angular levers 41 receive the pintles 42 of the paste roller 39, which is held against the wall paper as it passes over the roller 36, by 80 means of the springs 43. The upper ends of the springs 43 are connected to the upper ends of the levers 41, whereas the other ends of the springs 43 are connected at 44 to the sides 26. Secured at 45 to the outer 85 faces of the sides of the section 3 are opposite disposed plates 46, which are connected by a plurality of rods 47. Adjustably mounted on the rods 47 are plates 48, which are angular in plan view, there being set 90 screws 49 for holding the plates 48 in adjusted position, that is, when adjusted toward and from each other. Each of the plates 48 is slotted horizontally as shown at 50, to form the upper and lower arms 100 51 and 52. The rods 47 extend through the arms 51 of said plates 48, while the lower arms 52 are capable of yielding. The adjacent free end portions of the arms 51 and 52 of each plate 48 are constructed with recesses 54 and 55, in which the cutting members 56 and 57 are journaled upon the pins 58. The cutting edge portion of the cutting members (which are circular) overlap slightly, so that when the opposite edge 110 portions of the wall paper are passing through the slots 50 of said plates 48, the

edge portions of the wall paper are trimmed, by the cutting member. As the opposite edge portions of the paper are trimmed by the cutting members, the arms 52 yield 5 toward and from the arms 51. The roll 38 of wall paper is designed to be mounted upon a rod 60, which is mounted in bearings of the bracket arms 61 of the opposite sides 10 of the table. After the roll of paper is so mounted, the opposite edge portions of the paper are passed through the slots 50 of the plates 48, after which the paper is passed between the rolls 36 and 39. The paper is pulled from the roll 38, and as it 15 passes through the slots 50 of the plates 48 the opposite edges thereof are trimmed, and as the paper passes between the rolls 36 and 39, paste from the roller 39 is automatically applied to the paper. After the required 20 length of paper is trimmed and applied with paste, and is lying upon the upper faces of the bars 9 of the two sections of the table, a knife may be drawn transversely across the paper over the slot 63 (which is 25 formed by a strip or bar 64 being arranged parallel to but at a spaced interval from the bar 6), thereby severing the required length of paper from the main body of paper.

30 The invention having been set forth, what is claimed as new and useful is:—

1. In combination, a frame, oppositely disposed plates secured to opposite sides of the frame, a plurality of rods connecting the lower ends of said plates, a pair of plates angular in plan view being adjustable and toward each other and adjustably mounted upon said rod, said angular plates being slotted causing the formation of upper and lower arms, and through which 35 slot wall paper is adapted to pass, one arm of each angular plate being yieldable, and circular cutting members mounted in said 40 arms.

45 2. In combination, a frame, oppositely

disposed plates secured to opposite sides of the frame, a plurality of rods connecting the lower ends of said plates, a pair of plates angular in plan view being adjustable and toward each other and adjustably mounted 50 upon said rods, said angular plates being slotted causing the formation of upper and lower arms, and through which slot wall paper is adapted to pass, one arm of each angular plate being yieldable, and circular 55 cutting members mounted in said arms, and means for holding the angular plates in adjusted position.

3. In a wall paper trimming machine, the combination of a frame and a pair of hangers on the under face of the frame adjacent its opposite edges for the support of a roll of wall paper, of a pair of plates secured to the opposite edges of the frame and projecting downwardly, a plurality of rods 60 connecting the lower ends of said plates, a pair of wall paper guides on said rods, means for holding the guides on the rods, each guide in edge plan view being angular and constructed from a single plate, one 65 arm of each angular plate extending laterally outwardly, the other arm of each angular plate extending in a plane with the longitudinal plane of the frame, each plate being slotted through both arms forming 70 upper and lower parts, the upper part of the arm that extends in a plane longitudinal of the frame being carried on the said rods, while the lower part of each plate is yieldable, and circular cutting members mounted 75 80 in the extremities of the upper and lower parts of each plate.

In testimony whereof I have signed my name to this specification in the presence of two subscribing witnesses.

VIRDA R. BROWN.
